UNITED STATES PATENT OFFICE.

CLINTON E. WILDER, OF IRVINE, PENNSYLVANIA.

PIPE MOLD FOR CENTRIFUGAL CASTING MACHINES.

Application filed November 9, 1925. Serial No. 67,849.

This invention relates to molds for centrifugal casting machines.

The object of this invention is to provide a pipe mold for a centrifugal casting machine, having such exterior form that the metal wall thereof will be substantially uniform in thickness from end to end, so that its cylindrical wall will be free to expand without checking on the interior surface thereof.

Heretofore pipe molds for centrifugal casting machines have been made from forgings having sufficient metal at each end from which the sealing flange at one end and the driving flange at the opposite end are machined.

These flanges being removed from the source of heat, when the mold is in operation, do not expand, and therefore cause the interior surface of the mold to check at the end portions thereof. The present method of making the mold, requiring excess metal to be machined therefrom also increases the expense of manufacture.

In carrying out the object of my invention I make a forging of the necessary diameter for a pipe mold tube, and I place in the intake end of the finished mold, a throat ring, and upon the exit end of the mold tube a driving flange ring which throat ring and driving flange ring can be removed from the tube when desired. The throat ring, and driving flange ring, each being of comparatively light weight are easily handled while being machined, and are therefore of comparatively cheap construction, and when it becomes necessary to provide a new mold tube to replace one too much worn by use, the rings can be placed on the new tubes.

The features of my invention are herein-after fully described and pointed out, and are illustrated in the accompanying drawings, in which:

Figure 1 is a side elevation of a pipe mold for a centrifugal casting machine embodying my invention.

Figure 2 is an enlarged view of the same showing the ends thereof in vertical central section, with the intermediate portion broken away.

Figure 3 is a side elevation of my improved pipe mold tube with the throat and driving rings removed therefrom.

Figure 4 is an end view looking into the exit end thereof.

Figure 5 is a plan view of the left hand side of the driving ring.

Figure 6 is a central vertical section of the same.

Figure 7 is an enlarged fragmentary view of a portion of the same.

Figure 8 shows side and end elevations of the locking means for said ring.

In these drawings A indicates a pipe mold tube. Around the intake end *a* of the tube A are annular slots *a'* to form water seals when placed in a casting machine, not shown.

The interior of the intake end *a*, of the tube A is provided with an annular shoulder *A'* and with internal screw threads *A*², see Fig. 2.

Inserted into the intake end *a*, of the tube A is a throat ring B, which is provided with external threads *B'* which engage the internal threads *A*², and with an annular shoulder *B*² which engages the end *a* of the tube A, and projects beyond the shoulder *A'* on the tube A, thereby serving as an internal shoulder within the tube against which the molten metal engages thereby forming the end of the pipe being cast therein. The throat ring B is provided with recesses *b* around its exterior, which may be engaged by a spanner wrench to remove and replace the throat ring B upon the tube A.

The bell-shaped exit end of the mold tube A is provided with a cylindrical surface which is provided with external screw threads C, preferably of the square type, see Fig. 3, back of which is an annular flange C'. This flange C' is machined out, as shown in Figs. 2, 3 and 4, so that the wall of said flange C' is comparatively thin, which wall is provided with radial slots *c*, thus providing for a certain amount of yielding when the tube expands during operation.

Upon the cylindrical threaded surface C, I place a driving ring D, see Figs. 2, 5 and 6, which is provided with internal threads *D'* which engage the threads C on the tube. The ring D is provided with an annular shoulder *d* on its left hand side, see Figs. 2, 5, 6 and 7, which embraces the exterior of the undercut flange C' as shown in Fig. 2, said ring engaging the annular edge of said flange. The right hand side of the ring D is provided with an annular flange E which engages the annular end of the tube, so that said driving ring D will be firmly secured.

upon the bell shaped exit end of the tube A.

In order to provide means to securely lock the ring D, when in place, against relative rotation, I provide a recess F, in the inner

5 surface thereof, see Figs. 6 and 7, in which I place a semi-cylindrical block F', see Fig. 8, which is provided with a segment of threads f, which coincide with the internal threads D' of the ring D and engage the

10 threads C on the mold tube A. The ring D is also provided with a screw-threaded opening G on the axis of the recess F in which I place a screw G'; see Fig. 2, which engages

15 the block F' and is adapted to force the segment of threads f against the threads C on the tube A, thereby frictionally holding the ring D from rotating on the threads C.

It will thus be seen that the forging for the mold tube A will therefore need not con-

20 tain metal heretofore necessary for the seal and driving flanges at each end of the tube, which were heretofore necessary to be machined on a lathe large enough to carry the tube, but that the forging will only contain

25 enough metal for the tube as shown in Fig. 3, the intake end a, being of the same diameter as the intermediate portion of the mold tube, and that the necessary radial flange at the bell-shaped exit end of the

30 mold tube can be made separately, and put in place after the tube is finished, thus effect-

ing a great saving in material and labor.

Having thus fully described my invention so that others can utilize the same, what I

35 claim as new and desire to secure by Letters Patent is:

1. A pipe mold-tube the wall of which is of substantially uniform thickness throughout its entire length, and a driving ring re-

40 movably secured around the exit end of said mold-tube.

2. A pipe mold tube having an annular bearing slot around the intake end thereof, internal screw threads within the intake end

45 of said tube, a throat ring, external screw

threads thereon adapted to engage said internal threads, external screw-threads on the opposite end of said tube, a driving ring, and internal screw threads in said driving ring adapted to engage said external threads, 50 whereby said driving ring is removably secured on said mold tube.

3. A pipe mold tube having a bell-shaped exit end, an under cut flange around said exit end, axial slots through said undercut flange, 55 a cylindrical shoulder, screw threads on said shoulder, a driving ring, internal threads in said ring adapted to engage said external threads, an annular shoulder on said ring

50 adapted to receive said undercut flange on said tube, and an internal annular flange on said ring adapted to engage the end of the cylindrical shoulder on said tube.

4. A pipe mold tube, an undercut flange adjacent to one end thereof, a cylindrical 65 shoulder projecting beyond said flange, screw threads on said shoulder, a ring, internal screw threads therein, adapted to en-

60 gage the threads on said shoulder, a recess in said ring, a block in said recess, segments 70 of threads on said block adapted to engage the threads on said shoulder, and a screw mounted in said ring adapted to engage said block, whereby the same may be forced

65 transversely of the threads on said cylindrical shoulder.

5. A pipe mold consisting of a tubular shell of uniform thickness throughout its length, removable end rings therefor, and means to secure said rings in place on said

70 shell.

6. A pipe mold-tube the wall of which is of substantially uniform thickness throughout its entire length, a pair of spaced circumferential slots around the intake end of 85 said tube, and a throat ring adapted to be inserted into said tube to a point opposite the second of said slots.

In testimony whereof I affix my signature.

CLINTON E. WILDER.
